Primary Examiner — Catherine Tuttle*(74) Attorney, Agent, or Firm* — Kane Kessler, P.C.; Barry E. Negrin**CLAIM**

(57) The ornamental design for a beaded toy, as shown and described.

DESCRIPTION

FIG. 1 is a perspective view of the beaded toy showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines are included for the purpose of illustrating the portions of the beaded toy that form no part of the claimed design.

1 Claim, 4 Drawing Sheets
